Primary Examiner — Ruth McInroy(74) *Attorney, Agent, or Firm* — David A. Crowther(57) **CLAIM**

The ornamental design for a wind and noise blocker, as shown and described.

DESCRIPTION

FIG. 1 is a front perspective view of a wind and noise blocker showing my new design;

FIG. 2 is a left side elevation view thereof, the right side being a mirror image;

FIG. 3 is a bottom view thereof;

FIG. 4 is a front view thereof;

FIG. 5 is a top view thereof; and,

FIG. 6 is a rear view thereof.

The broken lines in the drawings show unclaimed subject matter only and form no part of the claimed design.
